JOHN C. HEBDEN, OF PROVIDENCE, RHODE ISLAND, AND FREDERICK H. DANIELL, OF FRANKLIN, NEW HAMPSHIRE.

YARN-SUPPORT FOR DYEING.

942,856.

Specification of Letters Patent.

Patented Dec. 7, 1909.

Original application filed November 10, 1908, Serial No. 461,911. Divided and this application filed April 10, 1909. Serial No. 489,143.

To all whom it may concern:

Be it known that we, JOHN C. HEBDEN and FREDERICK H. DANIELL, citizens of the United States, residing at Providence, in the 5 county of Providence and State of Rhode Island, and Franklin, in the county of Merrimack and State of New Hampshire, respectively, have invented certain new and useful Improvements in Yarn-Supports for 10 Dyeing, of which the following is a specification.

Our invention is a yarn support for use in dyeing and similar processes and consists of a novel form of holder for supporting 15 yarn packages or bobbins so that the latter may be nested together to form a continuous tubular mass of material with a central channel extending throughout its length.

Our invention relates particularly to the 20 dyeing or similar treatment of knitting bobbins or relatively large yarn packages which are adapted for use on knitting machines or for other purposes where an especially free delivery of the yarn is required.

25 The method of dyeing herein referred to constitutes the subject matter of an earlier application, No. 461,911, of which this is a division.

The device is fully described in the following specification, illustrated by the accompanying drawings, in which:

Figure 1 is a longitudinal sectional view of the bobbin holder or support with the form of the package shown by dot-and-dash 35 lines; Fig. 2, a longitudinal sectional view illustrating the method of arranging a plurality of bobbins under compression for subjection to the dyeing or other process; Fig. 3, a detail view of a part of the apparatus for supporting the bobbins in alinement under compression. Figs. 4 and 5 show modifications in the form and structure 40 of the holder.

In winding yarn for delivery to knitting 45 machines it is necessary that the bobbin be formed with a nose or delivery end of extreme taper so that the yarn may be unwound with the utmost freedom, without drag or resistance. The standard form of 50 knitting bobbin now in general use is what is termed a "bottle bobbin" and approximates a bottle in shape, having a flat base, a cylindrical body, and a tapered nose. This

form of bobbin is wound on a wooden holder (generally referred to as an empty bobbin, 55 when bare) having a comparatively long barrel or shank and a frusto-conical head or base at one end. The winding is started on the conical former or base and continued in conical layers superimposed on each other, 60 so that the bobbin has a uniform diameter throughout its cylindrical portion equal to the base of the holder, and a delivery nose of the same taper as the wooden base. The bobbins contain a large quantity of yarn, 65 several pounds, as a rule, and deliver from the conical end. It will be obvious that bobbins of this character are not adapted for dyeing or like processes. The solid core on which they are wound would prevent the 70 dyeing fluid from circulating through the mass and, besides this, the bobbins could not be suitably compacted and compressed to a proper density in the dyeing chamber to insure a uniform permeation. We believe that 75 it has never before been attempted to dye yarn in large packages or bobbins of this general form, but we have now devised a hollow, pervious holder which permits the nesting together of a plurality of these bobbins, so that the yarn masses may be subjected to compression, and an interior channel provided, with openings for the flow of 80 the liquor into the surrounding mass.

In Fig. 1, *a* represents the hollow, perforated holder or yarn support which is preferably made of sheet metal and shaped with a frusto-conical base portion *b* and a tube or barrel *c*. The base portion *b* corresponds in outward form to the solid head or butt of 90 the usual wooden bobbin and the tube portion *c* takes the place of the barrel or shank. It is preferable to form the tube portion with a slight taper, as shown, to provide for greater freedom of delivery as the yarn is 95 unwound therefrom. The holder *a* is perforated with a sufficient number of openings *d*, *d* etc. to provide for a free flow of the liquor. These are shown as relatively narrow, rectangular slits running the length of 100 the tube, this shape being preferable as it provides a better surface on which to wind the first layers of yarn whereas if the holes were wider the thread or yarn guide would be liable to catch in them as it traversed the 105 surface of the holder. At the same time

this form of perforation is not essential as small round or square holes would secure the same effect.

The yarn *y* is wound on the holder *a* in the usual manner for producing bobbins of this general form as represented by *A*. The first layers are deposited on the conical base portion *b* with a traverse equal to the length of the tapered portion of the base, and, as the winding continues, the traverse gradually shifts along the holder so that the bobbin grows by longitudinal extension, without any increase in diameter, until the end of the tube is reached. The perforations in the holder serve to roughen its surface slightly, so that the first coils wound on are prevented from slipping down from the tapered portion on to the barrel, but this roughness is not enough to prevent free delivery of the last few coils, in unwinding, because of the tendency of the yarn to fly out or "balloon" in delivering. With the previously mentioned wooden holder, now in general use, it is necessary to have the base covered with a rough cloth to prevent the coils from slipping, but with the present holder this is not required.

Fig. 2 illustrates the method of assembling the bobbins in units for subjection to the dyeing or other process, and also the manner of compressing the yarn into a continuous, tubular mass of uniform density. Any number of bobbins might be combined, but we have preferred to show a convenient number, three, assembled as now described: The bobbins are nested together in male-and-female fashion and for convenience in handling we provide the apparatus shown and described more particularly in our previous application, Serial No. 461,911, filed November 10, 1908. As shown in Fig. 2, this consists of a flange or base-plate *f*, formed with a tapered plug *g* and a central bore *h*. Secured to the base-plate *f* is a hollow, perforated, conical form *i*, adapted to fit the opening in the base end of the bobbin holder *a*. A similarly shaped, perforated form *j* is adapted to fit over the nose of one of the bobbins. The perforations *k* in the form *i* are graduated in size, with the largest holes near the small end, and similar perforations in the form *j* are also of graduated dimensions, but arranged in opposite relation, with the largest openings near the large end of the form, but not here shown. The purpose of this arrangement will be described later.

The form *j* is closed at its small end by a cap *m*, suitably secured thereto, and fastened to the inside of the cap by its end is a tie-piece or stringer *n*. The stringer *n* serves as a central support or skewer on which to string the bobbins and, while not absolutely necessary for their arrangement, is a convenient means for handling the bob-

bins in assembling them in units and in transporting them to and from the dye vat or keir. The preferred form of the stringer *n* is shown in the end view, Fig. 3, illustrating an angle-iron of V-shaped section of dimensions to adapt it to pass through the small end of the barrel *c* of the bobbin holder. The angle form of the stringer *n* provides for a channel through the openings in the bobbins, without obstruction to the flow of the liquor. At one end of the stringer its sides are bent out in the lips *o*—*o*, which are riveted or otherwise suitably secured to the cap *m*. At its opposite end the stringer is provided with a button or latch *p*, pivoted at *q* to allow it to be turned parallel with the stringer to pass through the bore *h* of the base-plate *f*. After the bobbins are assembled on the stringer, the base-plate *f* is set up against the base of the first bobbin *A*, with the form *i* entering the opening in the latter, and the end of the stringer *n* projecting through the bore *h*. The button *p* is then turned to engage the end of the plug *g* and the bobbins are thus held assembled in alignment in a unit adapted to be conveniently handled.

To force the cops together to compress the yarn masses, two headed rods *r*—*r* are carried through suitable holes near the rim of the flange *f*, the ends of the rods being threaded at *s*—*s*. A cross-piece *t*, having holes to receive the ends of the rods *r*—*r*, is placed with its boss or lug *u* against the end of the cap *m* and suitable hand-nuts *v*—*v* are screwed down on the rods. It will be obvious that a flange or plate might be substituted for the cross-piece *t* with any number of rods arranged around the outside of the bobbins, but for all practical purposes the two rods shown are sufficient.

By screwing the hand-nuts *v*—*v* down on the rods *r*—*r* the form *j* is pressed firmly down on the nose of the bobbin *A*³, and this bobbin, in turn, is forced downward to bring its base into close contact with the nose of the next bobbin *A*² and so on with all of the bobbins in the series; the bobbin *A* being forced on to the form *i* with its base tight against the base-plate *f*. Fig. 2 shows the bobbins drawn together in the manner above described, but before the dyeing fluid is applied it is advantageous to compress the bobbins slightly to insure that their yarn masses shall all be of uniform density and to prevent the liquor, or gas, if the latter is used, from escaping between adjoining ends of the bobbins. To effect this compression it is only necessary to screw the hand-nuts *v*—*v* still farther down on the rods *r*—*r*. The yarn between the form *j* and form *i* will then be compressed longitudinally of the axes of the bobbins into one continuous, tubular mass, with only the porous base-portions *b*—*b*, etc. of the holders intervening.

between the several bobbins. It will be understood that the stringer *n* is free to slide through the bore *h* of the base-plate *f*, as the latter and the form *j* are brought together under influence of the pressure of the cross-piece *t*. It will also be seen that the stringer *n* might be dispensed with except for the convenience of carrying the bobbins on it.

The plug *g* on the base-plate *f* is adapted to fit a bore *w* in a pipe or chamber *x* through which the dyeing fluid is supplied. The plug can be arranged to screw into this bore, or the base-plate *f* might be clamped down to hold it in position by any suitable means, as preferred. The arrangement and relation of the parts of the apparatus having now been particularly described the operation of the whole device used in connection with the yarn support or holder which forms the subject of the present invention will next be explained.

The bobbins having been wound on the hollow holders *a* they are assembled on the stringer *n* with the nose of each bobbin projecting into the hollow of the base of the next bobbin. Two ways of assembling the bobbins are available: The base-plate *f* may be set on the floor and the first bobbin *A* set on the form *i* and the succeeding bobbins *A²*, *A³* (and others, in series, if required) built up, one upon another. The stringer *n* is then run through the several holders, to skewer them together, and its end secured to the base-plate. It will be understood that the yarn can be compressed enough by hand to force the stringer through the base-plate far enough to allow the button *p* to be turned to engage it with the end of the plug *g*. Another method is to skewer the bobbins on to the stringer *n* first, and then apply the base-plate *f*. When a suitable number of bobbins have been assembled to fill the stringer, the cross-piece *t* is applied and pressed down on the cap *m* by means of the hand-nuts. This may be done before or after the base-plate is connected with the liquor supply chamber. As the yarn is compressed it contracts along the axes of the bobbins, the coils of winding closing up slightly at points where the bobbins are softest, so that finally the yarn mass is of uniform density throughout. It will be seen that the tubes *c* telescope, one within the other, to allow this contraction so that it is not necessary to employ contractible tubes. This is one of the advantages of forming the tube portion *c* of the holder *a* tapered, but a cylindrical tube might be used by adapting the construction of the tubes shown in our applications for patents now pending, Serial No. 417,419, filed February 24, 1908, and Serial No. 452,960, filed September 14, 1908, to this form of holder. Figs. 4 and 5 show two such forms of holders with their barrels constructed as fol-

lows:—In Fig. 4, the tube *c* is formed of a helically coiled wire *c²* which has its end coil riveted or otherwise fastened to the small end of the frusto conical base portion *b* of the holder *a*. The coil is surrounded by a tubular sleeve *c³* of reticulated fabric which serves as a cylindrical support for the yarn wound on the holder and prevents the coils of yarn from drawing down between the coils of wire. The sleeve *c³* is porous, being preferably made of a fabric of open mesh, so as to allow the passage of the dye liquor or other fluid.

Fig. 5 shows a form of holder having the tube *c* constructed from flat metal strips *c⁴*, *c⁵* coiled with their edges overlapping each other and perforated with holes *d*—*d* etc., similar to the holes in the base portion *b*. One end of the cylindrical tube *c* thus formed is secured in the small end of the base portion *b* by riveting or other suitable means. Instead of coiling two strips, a single strip might be coiled upon itself, and further, strips of wire screen cloth might be substituted for the perforated sheet metal.

With either of these forms of tubes just described the bobbins will be stacked for dyeing or other treatment in the same manner as before explained; the pointed end of one bobbin nesting in the hollow end of the next bobbin. It will be understood that when the bobbins are compressed along their axes the tubular portions of the holders, instead of sliding, one within another, will contract longitudinally to allow the compression of the yarn so that the same effect is secured as with the use of holders having tapered barrels.

The dye liquor, or other liquid or gas, according to the process contemplated, is supplied through the chamber *x*, and it is intended that a number of units of bobbins be treated at one time from the same supply, all being connected with the chamber *x* and inclosed in the same keir or vat. The liquor or gas is forced into the chamber *x* under pressure and passes through the bore *h* in the base-plate *f* into the opening or channel running through the tubes *c*. The cap *m* prevents escape of the fluid at the end of the series of bobbins and the perforations in the holders provide egress for the fluid from the tubes into the yarn mass. The base portions of the holders being also perforated, there will be no restriction of the flow of the liquor or gas at the points where the bobbins adjoin, so that, virtually, the whole yarn mass constitutes a porous tube susceptible to thorough permeation. The form *i*, as before explained, has the largest perforations nearest its small end, and the reason for this is, that as there is a greater proportion of the yarn mass contiguous to the holder at this point than at the large end of the form, it is advantageous to have a

freer flow of liquor where there is more resistance to its circulation through the yarn. For the same reason the form *j* has the largest perforations at the large end where, 5 in this case, there is more yarn, while the apertures are smaller at the small end where there is comparatively less thickness of yarn.

After the liquor or gas has been forced through the bobbins from the inside the 10 process may be reversed, if desired, and the liquor pumped back through the yarn from the outside, using the interior channel as an outlet or exhaust. After the dyeing process has been completed the yarn can be washed 15 by pumping water or a solution through the bobbins in the same manner, and, again, air or steam can be forced through them for drying purposes. Both the saturation and drying processes might be accomplished in 20 one container or keir but it has been found preferable to use a separate receptacle for drying, and it will be seen that the bobbin units can be handled very conveniently in changing from one to the other. It is not 25 required to separate the bobbins of the different units during the several operations, but it is only necessary to make new connections of the base-plates with the different 30 apparatus. After the bobbins have been treated and dried the cross-piece *t* is taken off and the stringer *n* removed. The yarn will then be in practically the same condition as when first wound, ready for delivery direct to the knitting or other machine. It 35 will be realized that the several rewinding processes necessary to convert the yarn from the skein, hank or cop, in which it is usually dyed, to the bobbin are thus eliminated and an immense saving in cost is therefore realized.

Having now described our invention and the particular method of its use in dyeing or otherwise similarly treating large masses of yarn in the form of commercial bobbins, 40 it is now pointed out that the novel feature for which we wish to secure protection is the improved form of yarn support or holder. While we are aware that the use of rigid, perforated tubes for dyeing yarn packages is not new in the art, we believe that the present invention possesses patentable novelty in that, heretofore, no attempt has been made to provide a holder for dyeing

yarn in this particular form whereby it can be compressed longitudinally of its support 55 notwithstanding said support is rigid.

The distinguishing feature of the invention is the means for supporting the yarn on a hollow base or former in conical layers continued throughout the whole length of 60 the bobbin and terminating in a tapered nose which is adapted to fit the corresponding opening in the base of an adjacent bobbin. This form of holder provides for the nesting of the bobbins together with the nose 65 of one bobbin fitted to the opening in the base of the next adjacent bobbin thus enabling us to compress the several masses of yarn between the conical forms of the supports (notwithstanding the fact that the 70 supports themselves are non-compressible) to produce a uniform density of the yarn and secure the advantages hereinbefore pointed out in the processes of dyeing or similar treatment of textiles. 75

What we claim is:—

1. The within described yarn support for use in treating yarn with fluids, comprising a hollow, porous frusto-conical base portion and a porous, tubular barrel connected 80 thereto.

2. The within described yarn support for dyeing, comprising a hollow, frusto-conical base and a tapered, tubular barrel projecting from the base, with perforations in the 85 base and barrel.

3. The within described yarn support, for use in treating textiles with fluids, formed of sheet metal with a hollow, frusto-conical base portion and a tubular barrel, with perforations in the base and barrel. 90

4. The within described yarn support for use in treating textiles with fluids comprising a hollow, frusto-conical base portion, and a tubular barrel projecting therefrom, 95 with narrow openings in the base and barrel portions extending in the direction of the axis of the support.

In testimony whereof we affix our signatures in presence of two witnesses.

JOHN C. HEBDEN.

FREDERICK H. DANIELL.
